[57] CLAIM

The ornamental design for a customer satisfaction terminal or the like, substantially as shown and described.

DESCRIPTION

FIG. 1 is a left-hand front perspective view of the customer satisfaction terminal, or the like, showing our new design;

FIG. 2 is a right-hand rear perspective view thereof;

FIG. 3 is a front perspective view with the keyboard in an alternate position from that of FIG. 1; and

FIG. 4 is a rear perspective view with the door illustrated in an alternate position from that of FIG. 2.

The bottom of the terminal is plain and unornamental.
The broken lines shown in the drawings are for illustrative purposes only.FIG. 1.

FIG. 2.

FIG. 3.

FIG. 4.
